UNITED STATES PATENT OFFICE.

HERMAN SCHELHAMMER, OF WHITESTONE LANDING, NEW YORK, ASSIGNOR TO
AMERICAN HARD RUBBER CO., OF NEW YORK, N. Y., A CORPORATION OF NEW
YORK.

MACHINE FOR REMOVING CORES FROM MOLDS.

Application filed April 12, 1921. Serial No. 460,767.

To all whom it may concern:

Be it known that I, HERMAN SCHELHAMMER, a citizen of the United States, residing at Whitestone Landing, in the county of 5 Queens and State of New York, have invented new and useful Improvements in Machines for Removing Cores from Molds, of which the following is a description, such as will enable others skilled in the art to 10 which it appertains to make and use the same.

This invention relates to machines for removing cores from molds, a principal object being to provide a machine of the above 15 class constructed to support a multiplicity of molds and to impart rapid vibrations thereto to effectively shake out, or remove, the cores therefrom.

A further object being to provide a machine of the above class of simple, strong, 20 inexpensive construction.

In the accompanying drawings there is illustrated different practical embodiments of the invention, but the constructions shown 25 therein are to be understood as illustrative only, and not as defining the limits of the invention.

Referring to the drawings:—

Figure 1 is a sectional side elevation taken 30 on the line 1—1 of Figure 3.

Figure 2 is a partial sectional plan view taken on the line 2—2 of Figure 3.

Figure 3 is a sectional end elevation taken 35 on the line 3—3 of Figure 2.

Figure 4 is a sectional end elevation showing a modified form of construction.

Figure 5 is a fragmentary view of a portion 40 of the construction shown in Figure 4.

Figure 6 is an end view showing a further modified form of construction.

Figure 7 is a plan view thereof.

In Figures 1, 2 and 3 of the drawings, 10 designates a suitable frame constituted by a base plate 11 and corner upright members 12, having horizontal bearings 13, for drive shafts 14, and provided at the top with vertical bearings or guides 15, to receive reciprocating pins or bars 16, adapted to carry mold supporting vibratory tables 17 and 15 which have pivotal connection at 18, with pitman-yokes 19 integrally formed with straps 20, to receive eccentrics 21, fixed to and revoluble with the drive shafts 14.

Power may be transmitted to the shafts 20, in any approved manner as, for instance,

by means of a pulley 22, fixed to one shaft, and a belt 23 applied to said pulley, said shafts being connected for simultaneous operation by a cross shaft 24, and bevel gears 25, as shown. 60

In operation, a plurality of molds 26 are placed on the tables 17, as clearly shown in Figures 1 and 3 of the drawings, with the edges thereof resting on the inner edges of the tables which are spaced apart in parallelism to provide a clearance, through which the cores indicated at 27, may pass when shaken free from the molds as will be readily understood. 65

In Figures 4 and 5 of the drawings, there 70 is illustrated a modified form of construction in which open cams 28, fixedly carried on the shafts 14, are employed to reciprocate the pins or bars 16 through anti-friction rollers 29, mounted in yokes 30, said rollers 75 being held in contact with the cams by push springs 31, arranged between the yokes 30, and the bearings or guides 15.

In Figures 6 and 7 of the drawings there 80 is illustrated a further modified form of construction, in which 32 designates a centrally arranged cylinder, having a piston 33 whose stem 34 carries a spider 35 having, in the form of construction shown, four arms 36, carrying the pins or bars 16, to support the 85 mold tables 17.

In the operation of this form of construction, air under pressure is admitted to the cylinder 32 through a pipe 37 and passes across the cylinder around a circumferential channel 38 formed in the piston 33, and from thence through a by-pass 39, back into the cylinder under the piston, and raises the same with its associated parts until an exhaust port 40 is uncovered, when the pressure 90 is destroyed, permitting a spring 41 to return the piston to its normal position, and this operation is repeated over and over again in rapid succession. 95

Of course it is desired to cover any equivalent arrangement whereby the above action can be obtained. 100

To expedite and facilitate the shaking loose of the covers from their molds, cushions 42 may be employed, positioned so that 105 the tables are slightly jarred at the end of the downward movement.

What I claim as my invention and desire to secure by Letters Patent, is:—

1. In a machine of the class described, a 110

frame, spaced mold supporting tables carried thereby and arranged to carry a mold having a core projecting below said tables and means for vibrating said tables in unison for the purpose specified.

2. In a machine of the class described, a frame, revoluble shafts mounted therein a pair of independent, mold supporting tables carried in the frame and arranged with a space between said tables for the reception of the projecting core of the mold, and means, when said shafts are rotated, for vibrating said tables in unison for the purpose specified.

3. In a machine of the class described, the combination with a mold having a core projecting therefrom, of a frame, revoluble shafts and reciprocatory bars mounted in said frame, independent, spaced, mold supporting tables on said bars and means on said shafts for vibrating the tables in unison for the purpose specified.

4. In a machine of the class described, a frame, shafts revolvably mounted therein, eccentrics on said shafts, vertical reciprocatory bars operatively connected with said eccentrics, means on said frame for carrying said bars, spaced independent tables on said bars for carrying a series of molds having cores adapted to project between said tables, and means for operating the shafts to vibrate the tables as and for the purpose specified.

5. In a machine of the class described a

frame, a pair of shafts connected one to the other for simultaneous rotation, reciprocatory bars carried by said frame, at the corners thereof, for operatively connecting said bars to said shafts, mold supports on said bars and devices on said shafts for vibrating said supports when the said shafts are operated.

6. In a machine of the class described, a frame, comprising a base and corner upright members having vertical guides and horizontal bearings, reciprocatory bars in said guides, mold supporting tables on said bars, shafts rotatably mounted in said bearings, devices on said shafts having operative connection with said bars, and means for revolving said shafts to vibrate the tables for the purpose specified.

7. In a machine of the class described, a pair of tables adapted to hold a series of molds therebetween with the cores of said molds projecting between said tables, means for vibrating said tables in unison, and means for cushioning the blow resulting from the downward drop of said tables.

In testimony whereof I have signed this specification in the presence of two subscribing witnesses.

HERMAN SCHELHAMMER.
